UNITED STATES PATENT OFFICE.

HENRY GEORGE VOLCKENING, OF BROOKLYN, NEW YORK, ASSIGNOR TO CHARLES K. VOLCKENING, OF BROOKLYN, NEW YORK.

POWDER PUFF.

Application filed January 31, 1928. Serial No. 250,757.

My invention relates to powder puffs and articles associated therewith and carried thereby, for use in beautifying and taking care of the face.

More particularly stated, my invention comprehends a powder puff of a simple construction and having a number of advantages, including cheapness of manufacture coupled with efficiency in operation.

My invention further comprehends a powder puff having a container of large size for holding a quantity of face powder, the powder puff also having a hollow handle for holding a quantity of oily or waxy material, such as rouge or some other cosmetic for beautifying the face.

My invention also contemplates a simple connection between the powder bag and the handle portion, for holding these parts detachably together and preventing leakage between them.

My invention also includes certain details of construction, for improving the general efficiency of powder puffs and parts immediately associated therewith.

Reference is made to the accompanying drawing forming a part of this specification, and in which like reference characters indicate like parts throughout the several figures.

Figure 1 is a plan view of one form of my invention, certain parts being shown as broken away.

Figure 2 is a substantially central cross section of the mechanism shown in Figure 1.

Figure 3 is a side elevation of the same.

Figure 4 is a perspective of the cap, forming a part of my device.

Figure 5 is a perspective showing another part of my device.

Figure 6 is a plan view of another form of my powder puff, showing the same as partly broken away.

I use two plies 7, 8 of flexible fabric, the plies 7 being provided with a centrally disposed opening 9. The ply 8 is permeable, for discharging a face powder in small quantities.

The two plies of material are so formed and fitted together that their peripheral edges 10, 11 are brought into registry with each other, and sewed together by stitches 12.

The stitching is preferably done upon a sewing machine, and the bag thus formed is

turned inside out, so as to bring the edges 10, 55 11 inward, as indicated in Figure 2. For this purpose, the opening 9 should be of sufficient size to facilitate turning the bag inside out.

I provide a large, flat ring 13, having a 60 neck portion 14 integral with it, this neck portion being provided externally with a thread.

The parts are so proportioned that the ring 13 may be forced through the opening 65 9 and thus brought within the bag, so as to leave the neck portion 14 protruding outwardly through this opening.

I provide a cylindrical member 15, having a thin portion 16 provided internally with a 70 thread making the thread of the neck portion 14. The cylindrical member 15 is provided with a partition 17, so arranged as to serve as a floor.

By fitting the thin portion 16 upon the neck portion 14 and turning the cylindrical member 15, this cylindrical member can be screwed down tightly upon the neck portion 14, so that the thin portion 16 grips and detachably holds the adjacent edge portion of 75 30 the ply 7.

It will be noted that the portion of the ply 7, thus gripped in position by the thin portion 6, is that portion of the ply which is bounded by the opening 9, so that this 85 opening is effectively closed.

The cylindrical member 15 is provided with an upwardly extending neck portion 19, threaded externally. A cap 20 is provided 90 with an annular flange 21, threaded internally and fitted upon the neck portion 19. That is, the cap 20 is a screw cap, detachably fitted upon the neck of the cylindrical member 15.

The cap 20 carries a mirror 22, this mirror being slightly convex and thus adapted for 95 producing a small image.

In order to use the mirror 22, the cap is removed, and turned or placed in such position as to face the operator.

A quantity of face powder 24 is placed 100 within the powder puff, and is replenished from time to time as exhausted by use.

In order to replenish the powder, the cylindrical member 15 is unscrewed and removed, the powder is poured in through the neck portion 14, and the cylindrical member 15 is then 105 replaced.

A supply of rouge 25, or analogous mate-

rial, is housed within the hollow cylindrical member 15, and is normally covered by the cap 20.

In order to use the rouge or analogous material 25, the operator unscrews the cap 20, takes it off, and thus obtains access to the material 25.

If the operator so desires, the mirror 22 may be brought into use, in order to facilitate the application of the material 25 to the lips, or to any other part of the face.

In Figure 6 I show a slightly different form of my invention from the one illustrated in the other figures.

15 A flat ring 26 is provided with a neck portion 27 like the neck portion 14 above described, the flat ring 26 being further provided with holes 28. By means of these holes, stitches 29 are made to extend through the ring 26 and through the adjacent portion of the ply 7. While the stitches 29 may be used if required, they are by no means essential in all cases, the adjacent edge portion of the 20 ply being held firmly in position by pressure of the cylindrical member 15, as above described.

The ring 13 with its neck 14, the handle member 15 and cap 20 may be severally made of metal, celluloid, hard rubber, casein, wood, 30 glass, papier mâché, or any other material found suitable for the purpose.

I do not limit myself to the precise mechanism shown, as variations may be made therein without departing from my invention, the 35 scope of which is commensurate with my claims.

Having thus described my invention, what I claim as new and desire to secure by Letters Patent is as follows:—

40 1. In a powder puff the combination of a bag serving as a container and provided with an opening, a flat ring located within said bag and provided with a neck extended through said opening, said neck being threaded, and a substantially cylindrical member provided with a threaded portion engaging said neck and further provided with an edge portion engaging the adjacent portion of said bag bounded by said opening, said substantially cylindrical member serving as a handle for the powder puff.

45 2. In a powder puff the combination of a containing member made of flexible material and provided with an opening of substantially circular form, said containing member being provided with a portion permeable in order to facilitate the discharge of a powder, a ring located within said containing member, a hollow cylindrical member connected with said ring and extending away from said containing member, said hollow cylindrical member serving as a handle and being provided with a compartment for holding rouge or the like, for use in connection 50 with powder puff.

3. In a powder puff the combination with a bag used as a container for a face powder or the like, of a flat ring located within said bag and provided with a neck extending through said opening, a hollow cylindrical member provided with a portion detachably engaging said neck of said ring, said hollow cylindrical member being provided with a partition and with a compartment bounded by said partition, and a cap detachably connected with said cylindrical body portion and normally covering said compartment therein, said cylindrical member serving as a handle for said bag.

4. In a powder puff the combination of a bag provided with an opening and serving as a container for a powder, said bag being provided with a portion which is permeable in order to facilitate the passage of small quantities of said powder through it, a ring located within said bag, and a hollow member detachably connected with said ring and coacting therewith for gripping the portion of said bag bounded by said opening, said hollow cylindrical member serving as a handle.

5. In a powder puff the combination of a bag made of flexible material for holding a powder, and provided with a portion permeable to said powder for discharging the same small quantities, said bag being provided with an opening, a flat ring located within said bag, a handle member connected with said ring and coacting with said ring for gripping a portion of said bag bounded by said opening, said handle member being provided with a compartment for holding rouge or the like, a cap detachably fitted upon said handle member and normally closing said compartment, and a mirror mounted within said cap and practically forming a part thereof, said mirror being removable along with said cap, and adapted for use as a face mirror.

6. In a powder puff the combination of a bag serving as a container and provided with a portion permeable to facilitate the discharge of small quantities of powder, said bag being further provided with an opening, a flat ring located within said bag and disposed adjacent said opening, said ring carrying a neck which extends through said opening, and a hollow cylindrical member detachably fitted upon said neck and provided with a portion engaging said bag along the edge of said opening and coacting with said ring to close said opening.

7. In a powder puff the combination of a bag serving as a container and provided with a portion which is permeable to a powder, said bag being further provided with an opening, a ring located within said bag and disposed adjacent said opening, said ring being provided with a plurality of small holes and carrying a neck which extends through said opening, stitches extending through said holes and through the adjacent portion of said bag,

a hollow member detachably fitted upon said neck and provided with a portion engaging said bag along the edge of said opening, said hollow portion serving as a handle for said bag.

8. In a powder puff the combination of a bag provided with an opening and serving as a container for a powder, said bag being provided with a portion which is permeable in order to facilitate the passage of small quantities of said powder through it, a gripping

member located within said bag, and a handle member connected with said gripping member and extending outwardly from said bag, said handle member coacting with said gripping member for gripping the portion of said bag bounded by said opening. ¹⁵

Signed at Brooklyn, in the county of Kings and State of New York, this 26th day of January, 1928.

HENRY GEORGE VOLCKENING.
